L. ROMINE.
SANITARY CLOSET SEAT.
APPLICATION FILED MAY 17, 1916.

Patented Aug. 8, 1916.

UNITED STATES PATENT OFFICE.

LAMBERTUS ROMINE, OF FRESNO, CALIFORNIA.

SANITARY CLOSET-SEAT.

1,194,073.

Specification of Letters Patent.

Patented Aug. 8, 1916.

Application filed May 17, 1916. Serial No. 98,042.

To all whom it may concern:

Be it known that I, LAMBERTUS ROMINE, a subject of the Queen of the Netherlands, and a resident of Fresno, in the county of Fresno and State of California, have invented a new and useful Improvement in Sanitary Closet-Seats, of which the following is a specification.

My invention is an improvement in sanitary closet seats, and has for its object to provide a seat of the character specified, wherein a supporting ring is provided of arched form for supporting a series of superposed sheets of toilet paper, which are adapted to be removed after use, and wherein a protecting cover is provided for protecting the sheets when not in use.

In the drawings: Figure 1 is a top plan view of the seat ring with the cover turned into open position, and Figs. 2 and 3 are sections on the lines 2—2 and 3—3, respectively, looking in the direction of the arrows adjacent to the respective lines.

The present embodiment of the invention comprises a ring 1 of rigid material, as for instance, sheet metal of a size to correspond with the size of the bowl 2, with which the ring is to be used, and the ring is arched transversely or radially as shown, and is arranged with its convex surface upward. The ring 1 is provided with holding clips 3, for engaging over the upper edge of the bowl to support the ring at the said upper edge and just within the same. These clips as shown more particularly in Fig. 3, are of suitable material shaped at one end to conform with the concave surface of the ring, and secured to the said face and shaped at the other end to engage over the upper enlarged edge 4 of the bowl. This ring 1 is adapted to support a series of superposed sheets 5 of toilet paper, the said sheets being in ring form and shaped to correspond with and fit upon the convex face of the ring. Preferably the sheets are superposed on a form or holder 6 of rigid material, as for instance, card board.

The device, as a whole, with the sheets superposed, is shaped to correspond with the contour of the ordinary seat ring, and the sheets 5 are adapted to be removed and destroyed after use. The sheets are formed by cutting them to shape by means of a stamp or the like, after which they are pressed to cause them to assume the arched or convex shape, and they may be marketed

in the same manner as toilet paper, each series of sheets being supported by its card board support 6.

In use, the user sits upon the superposed sheets, and after use the topmost sheet may be removed and destroyed, leaving thus a fresh and sanitary seat for the next user. The paper used is the ordinary toilet paper, as for instance, tissue or crape, and in order to prevent soiling the paper while emptying slops or the like into the bowl, a protective cover is provided.

The ring 1 is provided at the rear of the bowl with an angular lug 7, the said lug comprising a portion resting on the upper edge of the bowl and a portion extending upwardly therefrom. A ring-shaped frame 8 of wire or the like, is hinged to the lug 7, the frame having a hinged lug 9 for connection with the lug 7, and the cover 10, which may be of water proof material, as for instance, oil cloth, is shaped to correspond with the outline of the ring, and is secured at its outer edge to the frame in such manner that when the frame is folded down into the position of Fig. 2 the cover will cover and protect the said ring. In use, the frame with the cover may be turned upwardly out of the way.

I claim:

1. A seat ring for closet bowls of rigid material and arched transversely and arranged with its convex face upward, the ring having clips for engaging the upper end of the bowl to support the ring at the inner side and above the edge of the bowl, said ring supporting a series of superposed sheets of toilet paper in ring form and shaped to fit the convexity of the ring, a rigid form for supporting the sheets and fitting the ring, said ring having an upstanding lug at the rear of the bowl, a ring frame hinged to the lug and adapted to fold downward encircling the ring or upward, and a protective cover of water proof material secured to the ring and extending inwardly over the paper when the frame is in downward position.

2. A seat ring for closet bowls of rigid material and arched transversely and arranged with its convex face upward, the ring having clips for engaging the upper edge of the bowl to support the ring at the inner side and above the edge of the bowl, said ring supporting a series of superposed sheets of toilet paper in ring form and

shaped to fit the convexity of the ring, said ring having an upstanding lug at the rear of the bowl, a ring frame hinged to the lug and adapted to fold downward encircling the ring or upward, and a protective cover of water proof material secured to the ring and extending inwardly over the paper when the frame is in downward position.

3. A seat ring for closet bowls of rigid material and arched transversely and arranged with its convex face upward, the ring having clips for engaging the upper edge of the bowl to support the ring at the inner side and above the edge of the bowl,

said ring supporting a series of superposed 15 sheets of toilet paper in ring form and shaped to fit the convexity of the ring, said ring having an upstanding lug, a ring frame hinged to the lug and adapted to fold downward encircling the ring or upward, and a 20 cover connected to the ring and extending over the paper when the frame is in downward position.

LAMBERTUS ROMINE.

Witnesses:
